UNITED STATES PATENT OFFICE.

RALPH W. BERGSTROM, OF ROCKFORD, ILLINOIS.

LUBRICATING-OIL HEATER.

Application filed April 17, 1926. Serial No. 102,810.

This invention relates to a means for heating the lubricating oil which is circulated to various bearings of an internal combustion engine, and more particularly is concerned with a device for this purpose which may be conveniently installed and connected up for operation.

It is common practice in the design of an automobile engine to employ a pump for 10 circulating oil to various bearings or other points where lubrication is needed. For this purpose an intake pipe is arranged in the crank-case, usually close to its bottom, for taking oil therefrom to the pump. In order 15 to keep out impurities which may have gotten into the oil a fine mesh screen is commonly provided adjacent the intake whereby to filter the oil entering thereto. These several components in a lubricating system 20 may perform satisfactorily under ordinary conditions, but in cold weather the operation is not so good. This is due to the tendency of oil to congeal and even freeze at low temperatures, with a consequent failure or 25 inability to flow. Freezing usually results from the presence in the oil of an appreciable amount of water which must always be reckoned with. It is my object in this 30 invention to provide adjacent the intake within the crank case a heater which will quickly raise the temperature of the surrounding oil to a point at which it will readily flow to the pump, thus assuring a proper lubrication for the engine. Such a 35 heater, as I have designed it, is inexpensive to make, is unitary in character and hence easy to install, and requires no attention in service.

An exemplification of my invention in a 40 preferred form is set forth in the accompanying drawing in the manner following:

Figure 1 is a fragmentary vertical section adjacent the crank case bottom of an internal combustion engine;

Fig. 2 is a horizontal section therethrough taken on line 2—2 of Fig. 1;

Fig. 3 is a view in elevation looking toward the outer end of the heater unit as it appears when applied in place; and

Fig. 4 is a view showing the location of the heater appliance relative to certain associated parts of an automobile engine.

My heater per se may be in the form of a casting having a head plate 5 adapted 55 to overlie an opening of suitable size in one wall 6 of the crank case relatively close

to its bottom. Extending inwardly from this opening is a strainer element which, as shown, consists of a tube 7 having at its outer end an outturned flange 8 which may be fitted between the wall 6 and casting head 5. Interposed between this flange and the crank case wall 5 is a gasket 9 providing a seal when the casting is tightened in place as by means of stud bolts 10. The 60 strainer element is formed in part of a screen material 11 through which oil in the crank case may be filtered.

Extending inwardly from the head of the casting is a U-coil 12 which occupies space 70 interiorly of the strainer element. The casting head also provides a mounting for an intake pipe 13 which lies intermediately of the two branches of the U-coil. These parts—the intake pipe and U-coil—are mutually 75 symmetrical to each other and to the strainer element by which they are enclosed, and this relationship is assured by the fixed mounting of the pipe and coil on the head plate which in turn occupies a fixed position upon 80 the crank case wall which also affords a mounting for the strainer.

Upon the outer side of the plate connection may be made to the intake and coil, the former being joined by a tube 14 to an oil 85 circulating pump 15. To one end of this coil a connection 16 leads to the engine exhaust pipe 17, while the other coil end may have a connection (not shown) which leads the exhaust back into the pipe 17, or which 90 discharges the exhaust directly into the atmosphere. If desired a valve 18 may be placed in the connection 16 to shut off the heater when temperature conditions render 95 its operation unnecessary.

Among the advantages which inhere in my invention is a high efficiency in operation due to the fixed position of its components in a structure of unitary character. The heat is delivered close to the intake and 100 to the surrounding strainer whereby oil in the immediate vicinity is thermally affected quickly. In a very short space of time any frozen oil will be thawed out with the consequence that proper lubrication is assured 105 to the engine. At no time need any attention be paid to the heater. Its installation is simple indeed, and requires only the insertion through a hole of proper size in the crank case of the heating coil and intake 110 together with the usual strainer—the device may then be operated with knowledge that

its components interiorly of the crank case are in proper relationship for all time.

I claim:

1. A combined oil heating reservoir and strainer for the crank case of an internal combustion engine comprising, a head plate adapted for attachment to the crank case, an oil intake and an exhaust heater coil mounted on said plate, an imperforate cylindrical reservoir carried by said plate and surrounding said oil intake and exhaust heater coil, and a strainer carried by and enclosing the free end of said cylindrical reservoir.

2. A combined oil heating reservoir and strainer for the crank case of an internal combustion engine comprising, a head plate adapted for attachment to the crank case, an oil intake and an exhaust heater coil mounted on said plate, an imperforate cylindrical reservoir surrounding the major portion of 15 said oil intake and exhaust heater coil, and a cylindrical strainer member carried by the free end of said reservoir and enclosing the remainder of said oil intake and exhaust heater coil.
